UNITED STATES PATENT OFFICE.

PETER COUPER, OF OAKENHOLT, WALES.

PAPER-MAKING APPARATUS.

1,085,547.

Specification of Letters Patent.

Patented Jan. 27, 1914.

Application filed October 18, 1912. Serial No. 726,483.

To all whom it may concern:

Be it known that I, PETER COUPER, a subject of the King of England, and resident of Oakenholt, in the county of Flint, Wales, have invented an Improved Paper-Making Apparatus, of which the following is a specification.

This invention has reference to paper making apparatus of the kind described and illustrated in my prior Patent No. 819004 dated April 24th 1906. In such apparatus the green pulp is taken just as it leaves the straining plant and is concentrated before the bleach is added. This concentrated pulp is then delivered by the machine to a suitable vessel where the desired quantity of bleach is run among the fibers. The pulp is allowed to remain in the bleach liquid for some time until the required degree of whiteness is obtained. Then it is conveyed by a centrifugal or other pump through a pipe to said apparatus where the spent bleach liquor is extracted from the pulp, the concentrated fiber being delivered to a vessel where it is washed by the machine with clean water until no trace of chlorin remains. The washed pulp, preferably free from chlorin, is again delivered to my apparatus and concentrated to a very close consistency and 20 dried as if the pulp has been passed over a "press paté."

The aforesaid objects are attained by means of a drum with a perforated surface and having a series of compartments or buckets fitted inside, the said drum rotating inside an outer stationary casing, while a feed pipe and contracted mouth piece in combination with a centrifugal or other pump are so arranged as to deliver the wet pulp with force against the meshes of the perforated drum so that it is detained thereon, and the water is forced through said meshes and along the partitions inside the drum whence it is drawn off. Thus the 45 water drips through the perforated surface of the drum and is drawn off by gravity.

I am aware that it has been previously proposed to provide and arrange a suction box or suction boxes within the perforated 50 revolute shells or rollers or drums of paper making apparatus for the purpose of removing the water from the pulp, said suction boxes being either stationary or adapted to be adjusted axially or radially or both 55 and fitting with their open top tightly against the inner face of the rotating drum.

The leading features which distinguish the present apparatus, hereinafter described, from paper making machines of the kind described and from my patent previously referred to, consist herein that all compartments in the drum are dispensed with, further in the subsequent drawing off of the water dripping through the meshes of the drum by means of a suction box fitted to a slotted pipe, the latter extending through the drum and being adapted to be connected with a suction pump.

Further essential features of this invention consist in that the said pipe is mounted on standards and made vertically adjustable therein while a rubber ring fitted to the top of the open suction box insures an easy and tight fit with the interior of the rotating drum.

Other novel features are the provision of a device to recover the pulp from the machine back water and the arrangement at or near the mouth piece of the feed pipe of a slide which may be adjusted in order to prevent the water from rushing too freely over the top of the drum.

In order that this invention may be more clearly understood reference is made to the accompanying drawings in which:—

Figure 1 shows an end elevation of the apparatus; Fig. 2 shows a longitudinal section through Fig. 1; Fig. 3 shows a central section through Fig. 2, and Fig. 4 shows an end view of the apparatus somewhat modified, this design being particularly adapted for the recovery of the pulp from the machine back water.

With reference to Figs. 1, 2 and 3, provision is made of a rotary drum *a* having a perforated surface adapted to detain the fiber of the pulp at the same time allowing the liquid to drain through the said perforations. The drum is mounted upon sleeves *a¹*, *a²* the latter bearing in the ends *b*, *b¹* of a frame or pedestal, both sleeves and drum being rotated by means of wheel *c* and suitable gearing meshing therewith. As in my previous patent referred to above a mouth-piece *d* of a feed pipe *e* is arranged in close proximity to the surface of the drum through which the pulp is conveyed by means of a pump (not shown) and forced against the surface of said drum. In this manner the pulp is driven and spread against the meshes of the drum and collected and compacted thereon. Extending longi-

2
 tudinally through the drum and the sleeves is a pipe *f* having a slot *f*¹. The ends of said pipe are bearing in standards *g* and provided with flanges *h*, the latter serving 5 as a means to connect the pipe to a vacuum pump. Each end of the said pipe *f* is thus adapted to be connected to a suction pump (not shown) and has moreover a square piece *i* fashioned thereon which is guided in 10 a corresponding opening of the standards *g* and vertically adjustable by means of set screws *k* in order that the pipe may be raised or lowered as the case may be. Mounted upon the center part of the pipe *f* 15 is a suction box *l* of copper or gun metal into which the liquid drips and from the latter is sucked through the pipe *f* into any suitable vessel. The top of said suction box has fitted to it a rim *l*¹ of rubber which 20 bears against the inner face of the drum and causes a tight fit with the latter during its rotation. Arranged near the top of the drum is furthermore a rotary pressure roller *m* which by any known device, preferably 25 by the means as described in my prior specification, is adapted to press against the perforated surface of the drum thereby further concentrating the pulp. Provision is also made of a suitably mounted scraper or 30 "doctor" *o* which causes the removal of the concentrated pulp from the roller as the latter rotates.

Referring now to Fig. 4, this apparatus is specially designed for the recovery of the 35 pulp from the back-water of the machine. A felt *p* fitted over the drum and covering same is passed between and guided by press rollers *q* and *r*, which rollers are conveniently mounted on the frame of the machine. 40 In order to prevent the water rushing too freely over the top of the drum, I provide an easily adjustable slide *s* at a suitable distance from the mouth-piece *d*.

The action of the apparatus, Fig. 4, is as follows: Subsequent to the delivery of the 45 pulp on to the drum, the suction or vacuum pump draws the draining water through the felt and the drum into the suction box, then into the pipe *f* whence it is delivered into a vessel (not shown). The felt as it rotates 50 around the drum next passes between the press rollers *q* and *r* and the pulp and other matter is retained on the top side of the felt, but as it passes between the said press rollers, the top roller *q* picks up the particles of 55 fiber from the felt and the scraper or "doctor" removes it from this roller. *t* and *t*¹ designate press rollers between which the felt passes and *u* is a spray pipe serving to 60 rinse the felt.

Having now fully described my said invention what I claim and desire to secure by Letters Patent is:—

In the herein described paper making apparatus, the combination with a perforated 65 rotary drum, of sleeves for carrying the said drum, standards and a pedestal constituting the frame of the apparatus, a slotted vertically adjustable pipe bearing in said standards and extending through the drum 70 and the sleeves, a suction box fixed to the central portion of the pipe and communicating with the slot in the latter, a rubber rim fitted to the top of the suction box, a feed pipe to lead the pulp onto the said rotary 75 drum, and an adjustable slide near the mouth of said feed pipe, all substantially as specified and shown and for the purpose set forth.

In testimony whereof I have hereunto set 80 my hand in the presence of two subscribing witnesses.

PETER COUPER.
